UNITED STATES PATENT OFFICE.

JOHN SAURER, OF PHILADELPHIA, PENNSYLVANIA.

UMBRELLA.

SPECIFICATION forming part of Letters Patent No. 595,892, dated December 21, 1897.

Application filed August 5, 1897. Serial No. 647,273. (No model.)

To all whom it may concern:

Be it known that I, JOHN SAURER, a citizen of the United States, residing in the city and county of Philadelphia, in the State of Pennsylvania, have invented certain new and useful Improvements in Umbrellas, of which the following is a specification.

My invention relates specifically to the class of umbrellas which are adapted, to increase their portability, to fold into small compass, and it is the object of my invention to provide an umbrella frame of such construction as to be adapted to be easily folded both as to the handle and as to the individual ribs into very compact form.

In the accompanying drawings I show, and herein I describe a good form of a convenient embodiment of my invention, the particular subject-matter claimed as novel being hereinafter definitely specified.

In the accompanying drawings,

Figure 1 is a view in side elevation of the upper portion of the umbrella stick, the notch and its associated parts being removed for clearness of illustration.

Figure 2 is a view in side elevation of the lower portion of the umbrella stick, the runner being in section.

Figure 3 is a vertical section of one of the umbrella ribs and a portion of its spreader, the intermediate portions of the sections of the rib being broken away to reduce the length for convenience in illustration.

Figure 4 is an inside face view of one of the umbrella ribs, portions of each section being removed to reduce the length of the illustration.

Figure 5 is a view in perspective of the spring c^3 .

Figure 6 is a view in perspective of the locking plate c^2 .

Figure 7 is a view in perspective of the upper portion of one of the spreaders.

Figure 8 is a central sectional elevational view of the upper portion of the umbrella stick.

Figure 9 is a central sectional elevational view of an intermediate portion of the umbrella stick.

Figure 10 is a central sectional elevational view of the lower section of the umbrella stick, and a part of the intermediate section

of said stick, part of the said lower section being removed.

Figure 11 is a view in perspective of the upper portion of the stem J, and its associated parts.

Figure 12 is a sectional plan on the line 12—12 of Figure 8.

Figure 13 is a sectional plan on the line 13—13 of Figure 8.

Figure 14 is a sectional plan on the line 14—14 of Figure 9.

Figure 15 is a sectional plan on the line 15—15 of Figure 9.

Figure 16 is a sectional plan on the line 16—16 of Figure 9.

Figure 17 is a sectional plan on the line 17—17 of Figure 9.

Figure 18 is a sectional plan on the line 18—18 of Figure 10.

Figure 19 is a sectional plan on the line 19—19 of Figure 10.

Figure 20 is a sectional plan on the line 20—20 of Figure 10.

Figure 21 is a sectional plan on the line 21—21 of Figure 10.

Figure 22 is a sectional plan on the line 22—22 of Figure 10.

Figure 23 is a view in perspective of the rocking catch lever.

Figure 24 is a view in perspective of the upper portion of the tubular stem I.

Similar letters of reference indicate corresponding parts.

Referring first to the runner, spreaders, and ribs, the runner B is formed as a short tube encircling and adapted to run freely upon the umbrella handle, said runner being provided with projecting lugs between which is pivotally supported a rocking lever catch b' the nose b^5 at the lower end of which extends below the lower end of the runner and is curved inwardly so as to conveniently engage in a recess b^2 formed in the stick as shown in Figure 2, and the broad upper end of which forms a thumb piece b^4 and extends outwardly so as to be adapted to be readily found and pressed by the thumb of the user of the article.

b^3 is a flat spring secured to the body of the runner and operating against the under face of the thumb piece, b^4 , so as to constantly tilt or incline the rocking lever catch upon

its pivot and press the nose b^5 inward so that said nose shall automatically engage the recess b^2 in the umbrella stick whenever it is brought into position over said recess.

5 A recess b^2 corresponding to that shown in Figure 2 is formed in the upper end of the stick, to be engaged by the nose of the rocking lever catch when the runner is moved to its upper position in the opening or spreading of the umbrella.

The rocking lever is conveniently formed of sheet metal and its lower end is slightly twisted or bent so as to bring the flat metal into a position in which its plane coincides 15 with the axis of the stick, so that said lower end shall be the better adapted to resist the strain to which it may be subjected while engaged in the recess.

The upper end of the runner is provided 20 with the usual notches or recesses for the reception of the lower ends of the spreaders, C.

The ribs are formed in three sections designated respectively D E and F, which sections are each formed of a fillet of sheet metal, the 25 edges of which are curved upwardly so that said sections are of horseshoe shape in cross section, the three sections being of successively diminishing transverse area so as to be adapted to be nested together, the section 30 E within the section D, and the section F within the section E,—the three sections being arranged in telescopic relationship by virtue of which the rib as a whole may be at will drawn out to full length, or closed up so 35 as to occupy practically the length of but a single section.

The section D is provided as to its inner edges with the ratchet projections d (Figure 3), and its edges at its lower end are slightly 40 inturned to form the stop flanges d' (Figure 4).

The upper end of the section D is pivotally connected in any usual manner with the notch G, shown in Figure 8.

The section E is fitted as to its upper end 45 within the lower end of the section D, and is as to its upper end provided with a pair of lugs e (Figures 3 and 4), which project from the edges of said section above the stop flanges d' of the section D, so that said lugs and stop 50 flanges prevent the accidental withdrawal of the section E from the section D.

The upper end of the spreader C is provided with a pair of ears c' , Figure 7, which engage between the lugs e and are secured 55 thereto in hinged relationship by a suitable pivot upon which pivot is also hingedly secured a locking plate C^2 (Figures 3 and 6), the upper end of which is bent to form a shoulder which engages with the ratchet projection d , 60 being held in such position by the spiral spring c^3 , (Figures 3 and 5), coiled about the pivot, and bearing as to one end against the rear face of the locking plate c^2 to hold said plate constantly in engagement with the projection d ,—the other end of the spring c^3 65 passing down into the hollow interior of the spreader C.

The lower end of the section E is provided as to its edges with inturned flanges e' (Figures 3 and 4) and the upper end of the lower section F, which is entered in the lower end of the section E, is provided with outwardly turned flanges f (Figures 3 and 4) the arrangement being such that said flanges act as stops to prevent the withdrawal of the section F 75 from the section E.

The rear or outer face of the section E is at its lower end provided with an opening e^2 (Figure 3) and the section F is at the rear face of its upper end provided with an opening f' 80 which registers with the opening e^2 when the rib as a whole is extended.

f^2 is a spring coupler, in the form of a hook, the lower end of which is permanently attached to the section F, the shank of which 85 extends up along the hollow interior of the section F, and the rounded rear end f^3 of the head of which is forced by the resiliency of the shank through the openings $e^2 f'$, when said openings are in registry, said spring 90 coupler thus operating to maintain said sections temporarily in their extended position.

To further strengthen the hold of the coupler upon the section E, the stop flanges e' of said section E are provided with recesses, in 95 which a transverse bar f^4 seated at the free end of the bill of the hook, seats itself when the parts are in the extended position shown in Figures 3 and 4.

c^4 is a curved finger secured to the upper 100 end of the spreader C, and passing behind the pivotal connection of said spreader to the rib, said finger being of such form that when the umbrella is closed and the spreader and rib are brought into close proximity to each 105 other, said finger encounters the locking plate c^2 and elevates it out of contact with the ratchet projections d .

When the umbrella has been thus closed and said locking plate thus lifted out of contact with the projection d , and it is desired to shorten or collapse the ribs, axial pressure is, for such purpose, to be applied to the outer ends of said ribs, one at a time, in succession.

The first effect of this will be to carry the sections E and F together upwardly, the section E sliding (as it is made free to do by the elevation of the locking plate c^2) along the section D.

When the section E has been moved along so far that it lies almost entirely within the section D, the rounded end f^3 of the spring coupler f^2 will encounter the lower end of said section D, and be deflected inwardly, thereby 125 uncoupling, so to speak, the section F from the section E, so that the continued pressure applied to the section F will cause it to move inwardly along the section E with the result that when it has attained the limit of its inward movement all three sections will exist 130 in nested relationship.

The operation of extending the rib is simply the reverse of that described for collapsing

it, namely: downward traction is to be exerted upon the end of the section F, the result of which will be that it will be brought into the position shown in Figure 3, the locking coupler will automatically couple the sections E and F, and the locking plate c^2 will when the umbrella is opened, engage the ratchet teeth d , and secure the sections D and E in their extended position.

10 f^x are eyes mounted upon the exteriors of the rib sections, to which the silk or other cover of the umbrella may be temporarily or permanently secured in any desired manner.

The extensible stick with which my improved umbrella is equipped is formed in 15 three sections, composite respectively of three tube sections A' A² A³ of successively diminishing diameter from bottom to top, and telescopically related so that said stick may be 20 collapsed to bring the sections into nested relationship, with the result that said sections when in such nested position will occupy a space the length of which will be approximately one-third the whole length of the stick 25 when extended.

The stick tube A' which forms the body of the upper section of the umbrella stick, carries as hereinbefore stated, the umbrella notch G (Figure 8), and is formed with a pair of oppositely disposed transversely extending slots a' , as shown in Figures 8 and 12, and with a transversely extending web or filling block a^2 as shown in Figure 8, and the lower end of 30 said tube section A' is provided with an internal annular key plate a^3 having an approximately oval central aperture, as shown in Figures 9 and 17.

Within the tube section A' is mounted a 35 stem H, consisting of a pair of parallel plates, curved in cross section, arranged in concentric relationship, connected at their lower ends by an annular key plate h , secured to their inner opposing faces, and having an approximately oval central opening, the counterpart of the opening in the key plate a^3 , upon which key plate last mentioned the key plate h rests, as shown in Figures 9 and 16.

The upper end of the stem H is provided 40 with a solid plug H^x equipped with an axial stem h' , having a bearing in the filling block a^2 , said plug having also radially projecting studs h^2 which extend through the slots a' , and are entered in a revoluble collar h^x mounted upon the exterior of the section A' at a point 45 above the notch G.

50 h^3 is a spiral spring coiled about the stem h' , and having one end engaged in the web or filling block a^2 , and the other end engaged in the plug H^x, which spring operates to constantly throw said plug and its stem H, as far as possible to the right, (Figure 12), so that the studs h^2 engage against the ends of the slots a' .

The tube section A² of the stick encompasses and snugly fits upon the tube section A', and is provided with a tubular stem I of approximately oval section, concentrically

disposed within it, the upper end of which tubular stem I does not reach to the top of said section A².

70 The upper end of said tubular stem I extends through the apertures of the key plates a^3 , h , and is, above the key h , itself provided with an outwardly extending rigid flange or projection, i , as shown in Figures 9, 15, and 24, the circular edge of which flange is in close proximity to the inner faces of the curved plates H.

The tubular stem I is held against rotation or other movement with respect to the section A² being rigidly affixed thereto at its lower end as shown in Figure 10.

80 It is proper to here explain that the apertures in the key seats a^3 , h , and the cross section of the tubular stem I, hereinbefore referred to as oval, are not true ovals, but are of shape which may be described as of circular plan with oppositely disposed wings or extensions.

The tubular stem I fits within the aperture 85 of the key plate a^3 , and is held by its engagement in said aperture,—said aperture and stem being of the section described,—against rotation.

90 That part of the tubular stem I which exists within the aperture of the key plate h , however, is cut away as to its wings or lateral extensions i^x , as shown in Figure 24, so that only the central circular part of said stem remains within the central circular portion 100 of the aperture of said key plate h , with the result that said key plate h with the stem H to which it is rigidly connected, has rotation with respect to said tubular stem I.

95 The stem H is normally maintained by the 105 spring h^3 in such position that the aperture of the key plate h is rotated to a position in which its wings are out of registry with the wings of the aperture of the key plate a^3 ,—and when the parts are in such position, as 110 is obvious, the upper ends of the wings i^x of the tubular stem I encounter the under face of the side or solid portions of said key plate h , and the said key plate h with its connected stem, is prevented from descending, as it 115 would otherwise do, with the section A' down within the section A²,—while, on the other hand, the contact of the flange i against the upper face of said key plate H prevents the sections A' A² from being separated from each 120 other.

125 When it is desired to cause the section A' to descend within the section A² the device h^x is rotated against the stress of its spring, and thereby the stem H and key plate h are 130 rotated until the oval opening of said key plate h is in registry with the oval opening of the key plate a^3 , and the wings or lateral extensions of said openings in registry with the wings i^x of said tubular stem. When the 130 parts have been brought to this position, the section A' may be forced down within the section A², the key plates a^3 and h , both traveling down upon the exterior of the tubular

stem I, between which tubular stem and the outside wall of the section A³ descend the bodies of the stem H and section A'.

When after being closed it is desired to extend the stick and use the umbrella, the spring h⁸ will act, as soon as the parts reach the position shown in Fig. 9, to throw the key plate h with the wings of its openings out of registry with the wings of the opening of the key plate a³ and thus lock the parts in position.

The section A³ is provided with a solid central stem J, of circular section, the upper end of which reaches nearly to the upper end of said section, and is entered in the bore of the tubular stem I and provided with studs j which take into the wings of said stem.

The sides of the lower ends of the two wings i⁸ are cut away as shown, as is also the wall of the lower end of the tubular stem, to form a pair of slots k, Figure 11, so that traction may be exerted upon said stem J to draw it down so far, in the opening or extending of the stick, that its studs emerge through the open lower ends of the wings i⁸, whereupon rotation imparted to said stem J will carry said studs into registry with said slots into which they will be carried, to lock the stick in extended position, by a spring k', bearing against a projection j' of said stem J and the partially closed lower end of the section A³.

The lower end of the stem J protrudes through the lower end of the section A³ and is beyond said end equipped with a thimble L which encompasses the end of said section A³ and may be of any desired fanciful configuration.

Arms J^X rigidly secured to the stem J protrude through L-shaped slots M in opposite sides of the section A³ and are attached rigidly to said thimble L with the result that movement imparted to said thimble will be transmitted to said stem.

The umbrella stick being supposed extended as shown in Figures 8, 9, and 10, when it is desired to shorten the same the section A' is forced down within the section A³ in the manner hereinbefore at large explained.

To force the section A² (containing the section A') down within the section A³ the thimble L is grasped and drawn outward carrying with it of course the stem J until the arms J^X reach the lower end of the L-shaped slots M.

When said arms have reached this point the studs j have been carried out of the slots k, whereupon rotation imparted to said thimble until the ends of the lower branches of the L-shaped slots are encountered by the arms J^X, will carry the studs j into the wings or lateral extensions i⁸ of the tubular stem I.

Thereupon said section A² may be forced down within the section A³ said wings or lateral extensions i⁸ sliding down past said studs j.

The operation of withdrawing the section A² from the section A³ is reverse of the operation just described.

From a consideration of the construction

shown and described it is manifest that the device h⁸ and the device L are to be rotated in opposite directions in the shortening of the umbrella stick, and it will be understood that the user is supposed to grasp said device h⁸ in one hand and the device L in the other hand and to contemporaneously rotate them in opposite directions and thereupon immediately force the ends of the extended stick toward each other.

Having thus described my invention, I claim and desire to secure by Letters Patent—

1. In a folding umbrella, in combination with a collapsible stick, a series of ribs pivotally connected thereto, each of said ribs being formed of three sections assembled in telescopic relationship, spreaders extending from said stick to said ribs, devices disposed in connection with the joints between the first and second sections of the ribs and operative in connection with devices carried by the spreaders to lock said first and second sections of the ribs in extended position when the umbrella is open, and devices disposed in connection with the joints between the second and third sections of the ribs which automatically lock said sections, when extended, in their extended positions, the arrangement of the parts being such that when the ribs are lowered pressure applied to their outer ends causes, first, the second sections to slide within the first sections, and, second, the tripping and release of the locking devices at the joints between the second and third sections to enable the third sections to be forced within the second sections, substantially as set forth.

2. In a folding umbrella, a rib having two sections composed of sheet metal of U-shaped section, and telescopically related, the uppermost of which is pivotally secured to the notch of the umbrella, a stop flange, formed on the lower end of said section, a projecting lug formed on the second section above said stop flange, a spreader pivotally connected to said projection, a ratchet tooth formed on the uppermost of said sections, a locking plate carried by the spreader and adapted to engage said tooth, a spring which constantly forces said locking plate against said tooth, a finger mounted upon the upper end of said spreader and adapted when the umbrella is closed to encounter said locking plate and elevate it out of contact with the tooth, substantially as set forth.

3. An umbrella stick composed of a series of sections assembled in telescopic relationship, the upper section being provided with an internal rotatable stem, and a second section being provided with an internal fixed stem of non-circular cross section, a key-plate mounted on the lower end of the stem of the upper section, said key-plate having an aperture corresponding to the cross section of the tubular stem of the second section, substantially as set forth.

4. An umbrella stick composed of a series of sections assembled in telescopic relationship, the upper section being provided with an internal rotatable stem, and a second section being provided with an internal fixed stem of non-circular cross-section as to its body, but of circular section in the vicinity of its upper end, and a key-plate mounted on the lower end of the stem of the upper section, said key-plate having an aperture corresponding to the cross-section of the tubular stem of the second section, and being seated upon the circular portion of the tubular stem of the second section, substantially as set forth.

5. An umbrella stick composed of a series of sections assembled in telescopic relationship, the upper section being provided with an internal rotatable stem, and a second section being provided with an internal fixed stem of non-circular cross-section as to its body, but of circular section in the vicinity of its upper end, a key plate mounted on the lower end of the stem of the upper section, said key-plate having an aperture corresponding to the cross-section of the tubular stem of the second section, and being seated upon the circular portion of the tubular stem of the second section, and a spring which normally maintains the stem of the upper section in a position in which the aperture of its key-plate is rotated out of registry with the non-circular body of the stem of the second section, substantially as set forth.

6. An umbrella stick composed of a series of sections assembled in telescopic relationship, the upper section being provided with an internal rotatable stem, and a second section being provided with an internal fixed stem of non-circular cross-section as to its body, but of circular section in the vicinity of its upper end, and a key plate mounted on the lower end of the stem of the upper section, said key-plate having an aperture corresponding to the cross-section of the tubular stem of the second section, and being seated upon the circular portion of the tubular stem of the second section, a spring which normally maintains the stem of the upper section in a position in which the aperture of its key-plate is rotated out of registry with the non-circular body of the stem of the second section, a rotatable device mounted upon the exterior of said upper section, a slot formed in the wall of said upper section, and a stud passing through said slot, and connecting said rotatable device with said internal rotatable stem, substantially as set forth.

7. An umbrella stick composed of a series of sections assembled in telescopic relationship, the upper section being provided at its lower end with an internal key-plate, a rotatable stem mounted in said upper section, and provided at its lower end with a key-plate resting upon the key-plate first mentioned, non-circular apertures formed in said key-plates, a tubular non-circular stem mounted

in the second section and extending as to its upper end through the apertures of said key-plates above which it is provided with a flange, that portion of said stem which exists within the key-plate of the stem of the upper section being so formed as to be of circular cross-section, the cross-section of the non-circular body of the tubular stem of the second section and the non-circular apertures in the key-plates being all of the same outline, substantially as set forth.

8. An umbrella stick composed of a series of sections assembled in telescopic relationship, the upper section being provided at its lower end with an inturned key-plate, a rotatable stem mounted in said upper section, and provided at its lower end with a key-plate resting upon the key-plate first mentioned, non-circular apertures formed in said key-plates, a tubular non-circular stem mounted in the second section and extending as to its upper end through the apertures of said key-plates above which it is provided with a flange, that portion of said stem which exists within the key-plate of the stem of the upper section being so formed as to be of circular cross-section, the cross-section of the non-circular body of the tubular stem of the second section and the non-circular apertures in the key-plates being all of the same outline, a spring which normally maintains the stem of the upper section in a position in which the aperture of its key-plate is out of registry with the aperture of the key-plate of the upper section, substantially as set forth.

9. An umbrella stick composed of a series of sections assembled in telescopic relationship, the upper section being provided at its lower end with an inturned key-plate, a rotatable stem mounted in said upper section, and provided at its lower end with a key-plate resting upon the key-plate first mentioned, non-circular apertures formed in said key-plates, a tubular non-circular stem mounted in the second section and extending as to its upper end through the apertures of said key-plates above which it is provided with a flange, that portion of said stem which exists within the key-plate of the stem of the upper section being so formed as to be of circular cross-section, the cross-section of the non-circular body of the tubular stem of the second section and the non-circular apertures in the key-plates being all of the same outline, a spring which normally maintains the stem of the upper section in a position in which the aperture of its key-plate is out of registry with the aperture of the key-plate of the upper section, and a manually operated device mounted upon the exterior of said upper section and connected to the internal stem of said upper section, by which rotation may be imparted to the stem of said upper section against the stress of its spring, substantially as set forth.

10. An umbrella stick composed of a series of sections, assembled in telescopic relation-

ship, the lower-most section being provided with a central stem having projecting lugs, a second section which is adapted to slide within said lower-most section, being formed 5 as a double walled structure the inner wall of which constitutes a tubular stem having wings, the stem of the lower-most section being adapted to fit within the body and its studs to fit within the wings, of said tubular 10 stem, substantially as set forth.

11. An umbrella stick composed of a series of sections, assembled in telescopic relationship, the lower-most section being provided with a central stem having projecting lugs, a 15 second section which is adapted to slide within said lower-most section, said second section being formed as a double walled structure the inner wall of which constitutes a tubular stem having wings, the stem of the lower-most 20 section being adapted to fit within the body and its studs to fit within the wings, of said tubular stem, the lower end of said tubular stem having openings through the lower ends of the wings, and slots in its side body, sub- 25 substantially as set forth.

12. An umbrella stick composed of a series of sections, assembled in telescopic relationship, the lower-most section being provided with a central stem having projecting lugs, a 30 second section which is adapted to slide within said lower-most section, said second section being formed as a double walled structure the inner wall of which constitutes a tubular stem having wings, the stem of the 35 lower-most section being adapted to fit within the body and its studs to fit within the wings of said tubular stem, the lower end of said tubular stem having openings and slots as described, the stem of the lower-most section be- 40 ing adapted for slight longitudinal and rotary motion independent of said lower-most section, so that it may be drawn down to carry its studs out of the wings of the tubular stem, and turned to carry them into engagement 45 with the slots, substantially as set forth.

13. In combination, in an umbrella stick composed of a series of sections arranged in

telescopic relationship, a lower-most section having a stem provided with studs, a second section adapted to slide within said lower- 50 most section, and provided with a tubular stem embodying wings and slots, the stem of the lower-most section protruding through the ends of said section and being equipped with a manipulating thimble, substantially as set 55 forth.

14. In combination, in an umbrella stick composed of a series of sections arranged in telescopic relationship, a lower-most section having a stem provided with studs, a second 60 section adapted to slide within said lower-most section, and provided with a tubular stem embodying wings and slots, the stem of the lower-most section protruding through the end of said section and being equipped 65 with a manipulating thimble, a stop mounted on said stem, and a spring interposed between said stop, and the lower end portion of said lower-most section, substantially as set forth.

15. In combination, in an umbrella stick 70 composed of a series of sections arranged in telescopic relationship, a lower-most section having a stem provided with studs, a second section adapted to slide within said lower- 75 most section, and provided with a tubular stem embodying wings and slots, the stem of the lower-most section protruding through the end of said section and being equipped with a manipulating thimble, a stop mounted on said stem, and a spring interposed between 80 said stop and a lower end portion of said lower-most section, an L-shaped slot formed in the wall of the lower-most section, and an arm passing through said slot, and connecting 85 said stem to said manipulating thimble, sub- stantially as set forth.

In testimony that I claim the foregoing as my invention I have hereunto signed my name this 21st day of July, A. D. 1897.

JOHN SAURER.

In presence of—

F. NORMAN DIXON,
L. P. YERKES.
